UNITED STATES PATENT OFFICE.

FREDERICK G. COOPER, OF NEW HAVEN, CONNECTICUT.

FURNACE.

SPECIFICATION forming part of Letters Patent No. 727,750, dated May 12, 1903.

Application filed October 1, 1901. Serial No. 77,233. (No model.)

To all whom it may concern:

Be it known that I, FREDERICK G. COOPER, a citizen of the United States, residing at New Haven, in the county of New Haven and State 5 of Connecticut, have invented certain new and useful Improvements in Furnaces, of which the following is a specification, reference being had therein to the accompanying drawings.

10 My invention relates to improvements in furnaces, which improvements can be applied to any form of heating apparatus, whether for commercial or family use, but, as herein described, refer more especially to that type of 15 furnace known as a "hot-air" furnace.

It is the object of my invention, among other things, to construct a furnace in which the products of combustion after passing from the combustion-chamber are distributed, so as to provide for the largest possible 20 radiating-surface, and are again subjected to the influence of the heat within the combustion-chamber, by which they are reheated before passing out through the smoke-flue into 25 the chimney, and to so construct the parts that the direct outlet from the combustion-chamber into the smoke-flue shall preferably be in the dome thereof above the feed-door, it being a further object of my invention to 30 use means whereby the device can be readily adapted to any of the various types or forms of furnaces.

To these and other ends my invention consists in the furnace having certain details of 35 construction and combination of parts, as will be hereinafter described, and more particularly pointed out in the claim.

Referring to the drawings, in which like numerals designate like parts in the several figures, Figure 1 is a sectional elevation of one 40 form of a furnace embodying my invention, and Fig. 2 is a sectional plan view thereof upon line A B of Fig. 1.

In the practice of my invention I provide 45 the ordinary furnace with a plurality of down-takes which open at their upper ends into the combustion-chamber and at their lower ends into a horizontal chamber. A single uptake connects this horizontal chamber with the 50 smoke-flue and passes into the upper portion of the combustion-chamber. The smoke-flue is preferably arranged in the dome of the fur-

nace and provided with a damper, whereby a direct passage may be opened from the combustion-chamber to the chimney.

55

In the drawings the numeral 1 designates the outer casing or shell of the furnace, having the collars 2 thereon for connection with the hot-air pipes.

Within the interior of the casing 1 is the 60 furnace-body 3, having therein the combustion-chamber 4, grate 5, lining 6, surrounding the fire-pot, and opening into the fire-pot from the exterior of the shell 1 is the feed-passage 7, closed at its outer end by the feed-door 8. As all of these parts can be constructed in any preferred manner, I do not limit myself to the exact construction herein shown and described.

Surrounding the base of the body 3, within 70 the outer casing 1, is the horizontal parti-circular pipe 9, connected with the combustion-chamber by a plurality of downtake-pipes 10, which open into the combustion-chamber at their upper ends, as at 11. The number 75 and size of these downtake-pipes can be varied as desired, it being an advantage of course to provide the maximum amount of radiating-surface for the heated gases, which travel in a downward course through these 80 pipes. Projecting upwardly from the horizontal pipe 9 is the uptake-pipe 12, which enters the combustion-chamber near the dome and opens into the smoke-pipe 13, which passes outward through the outer casing 1 85 and is connected with the chimney in any manner well known in the art.

Connected with the smoke-pipe 13 and the outer casing 1 is the check-draft pipe 14, which is closed at its outer end by a door 15, 90 of any usual or preferred construction, and mounted within the lower end of the smoke-pipe 13, so as to open or close the direct passage from the combustion-chamber to the chimney, is the damper 16, which is actuated 95 by the rotatable damper-rod 17. The check-draft pipe 14 can be omitted, if desired, without affecting the operation of my invention.

As the gases and products of combustion rise from the fire in the fire-pot into the dome 100 of the combustion-chamber they escape through the openings 11 into the downtake-pipes 10 and enter the horizontal chamber within the pipe 9. While in the downtake

and tube 9 the temperature of the gas, &c., is lowered by the contact of the cooler air within the outer casing 1 with these pipes. The gases, &c., escape from the pipe 9 into the uptake 12 and enter the smoke-pipe 13 through the horizontal portion of said pipe 12 within the combustion-chamber. The heat within the combustion-chamber reheats the gases within the horizontal portion of the pipe 12, which increased temperature rarefies and lightens these gases, &c., which now move more rapidly and with a much accelerated movement into the smoke-pipe 13 and are immediately replaced by those gases with a lower temperature immediately following, thus increasing the pull or draft through the downtakes from the combustion-chamber, irrespective of the normal draft through the ash-pit or grate.

20 As the direct connection with the smoke-pipe is in the top of the combustion-chamber, the exit for the gases is in the most convenient place and permits practically all of it to escape when the damper is opened, and if this is done before the feed-door is opened the gases escape into the chimney and do not enter the room through the feed-passage and door, as is common in furnaces at the present time.

30 It is, of course, readily understood that a direct draft is created in the fire-pot by opening the damper when it is desired to start a fire or for other purposes.

With a furnace having my improvements 35 the products of combustion reach the chimney through indirect passages and are reheated, which increases the draft and accelerates their movement through the radiating-passages, permitting an increased amount of 40 such radiating-surfaces and a longer travel of the heated gases. The location of the smoke-pipe in the dome of the furnace permits the placing of the direct damper directly over the fire, and as the outlet into the smoke-pipe can 45 be of any size the gas-pressure in the com-

bustion-chamber can be the more readily relieved than when the direct outlet is upon the back of the furnace and on substantially a line with the feed-door, as is usual.

I desire to be understood that the number, 50 shape, or size of the up and down take tubes or flues and other parts can be varied indefinitely.

There are minor changes and alterations that can be made within the spirit and scope 55 of my invention aside from those herein shown and suggested, and I would therefore have it understood that I do not limit myself to the exact construction herein shown and described, but claim all that falls fairly within 60 the spirit and scope of my invention.

I am aware that furnaces have been heretofore made with an uptake passing directly from the fire-pot and surrounded with coal or other combustible material, and I therefore 65 do not claim such construction, but limit myself to a furnace in which the uptake passes through the combustion-chamber above the fire-pot and the combustible materials therein.

What I claim as new, and desire to secure 70 by Letters Patent, is—

In a furnace, the combination with the combustion-chamber; of a gas-receptive chamber 9 below the said combustion-chamber; a plurality of downtakes 10 opening into said combustion-chamber adjacent to the top thereof and into the said gas-receptive chamber at their lower ends; and an uptake 12 connecting said gas-receptive chamber with the smoke-flue, said uptake passing through said combustion-chamber adjacent to the upper end thereof and above the fire-pot before joining with the smoke-flue, all constructed and operating substantially as shown and described.

In testimony whereof I affix my signature 85 in presence of two witnesses.

FREDERICK G. COOPER.
